UNITED STATES PATENT OFFICE

JOHN EKERN OTT, OF CHICAGO, ILLINOIS, ASSIGNOR TO ACME STEEL COMPANY, OF CHICAGO, ILLINOIS, A CORPORATION OF ILLINOIS

BOX-STRAP SEAL

Application filed May 10, 1928. Serial No. 276,566.

This invention relates to improvements in box strap seals and its purpose is to provide a device for use in connection with a plurality of flat metal straps or other binders which are passed around boxes or other packages for reinforcing purposes. The principal object of the invention is to provide an improved device for connection with angularly disposed straps encircling a box or package for the purpose of preventing these straps from being slipped sidewise and thereby removed. A further object of the invention is to provide a seal having angularly disposed parts each provided with means for forming an interlocking engagement with a strap or other binder. A further object of the invention is to provide a sealing device having two right-angularly disposed arms each provided with parallel flanges adapted to be bent over a strap and to be sealed in that position by a suitable sealing tool. Other objects relate to various features of construction and arrangement pointed out more fully hereinafter.

The nature of the invention will be understood from the following specification taken with the accompanying drawings in which one embodiment is illustrated. In the drawings—

Fig. 1 shows a perspective view of a wooden box having two rightangularly disposed encircling straps applied thereto and connected by the improved seal of the present invention;

Fig. 2 shows an enlarged top plan view of the intersecting portions of the strap and the connecting seal;

Fig. 3 is a detail sectional view taken on the line 3—3 of Fig. 2;

Fig. 4 is a perspective view of the open seal before it is applied to the straps; and

Fig. 5 is a view similar to that of Fig. 2, showing the use of the seal for securing the overlapping ends of each strap.

As illustrated in Fig. 1, the wooden box 10 has applied thereto two flat steel straps 11 and 12 which are located midway between the corners of the box and which encircle the box in two rightangular planes so that they cross each other at the centers of the top and bottom of the box. The ends of the strap 11 and 12 overlap each other as shown at 11^a and

12^a, respectively, and these overlapping ends are secured together by seals 13 which are preferably of the form described and claimed in the patent of Ralph H. Norton No. 1,260,016, granted March 19, 1918. Before the seals 13 are applied and operated upon by a sealing tool to form the depressed portions 13^a and thereby partially shear the edges of the seal and of the overlapping portions of the strap, the strap is stretched taut so that when the seal is applied the strap is maintained tightly around the box. Even with this tight arrangement of the straps, they might be moved edgewise on the box and detached entirely therefrom unless they be interconnected at their intersections or attached to the box by nailing or the like. Since the use of nails or other fastening means is objectionable, it is desirable to prevent the movement of the straps by other means.

The present invention provides securing means in the form of an interconnecting seal 14 which is applied to the straps 11 and 12 adjacent the point of intersection 15 on the top of the box. Each seal is formed initially as illustrated in Fig. 4 and comprises a flat plate 14^a having two right-angular arms 14^b each of which has two downwardly extending parallel flanges 14^c along its lateral edges. The ends of these flanges are preferably inclined as shown at 14^d and after the straps 11 and 12 have been applied to the box and the seals 13 secured thereon, the open seal may be applied to the crossed straps 11 and 12 by slipping the flanges 14^c downwardly thereover with one pair of flanges engaging each of the straps.

A suitable sealing tool, such as that shown in the co-pending application of Messrs. Mac-Chesney and Ott, Serial No. 149,307, filed November 19, 1926, or that shown in my application Serial No. 276,565, filed May 10, 1928, may be passed into engagement with the seal to form the crimps 16 and to correspondingly shear the edges of the seal and of the straps. The formation of the depressions 16 shears the edges of each arm 14^b of the seal 14 and at the same time shears the edges of the straps 11 and 12 so that the seal 14 has an interlocking connection with each of the straps and cannot be removed there-

from. In this way the two straps are positively connected at the point of intersection and neither strap can be moved from its position on the box. Of course, any number of 5 crossed straps may be connected by means of the seals 14 and the straps may be located in various positions around the box or other package. The same sealing tool may be used in securing the seal 14 in place that is employed in securing the overlapping ends of the strap together by means of the seals 13 so that the advantages of the present invention may be obtained without any additional equipment other than the open seals of the 10 form shown in Fig. 4.

15 In Fig. 5 of the drawings there is illustrated the use of the seal of the present invention for securing together two crossed binders or straps and at the same time uniting the overlapping ends of each strap, thus giving a 20 double function to the seal 14 and making it unnecessary to use the additional seals 13 shown in Fig. 1. In the arrangement shown in Fig. 5, the two straps 21 and 22 cross each 25 other at right angles with their ends overlapping at the points of intersection as shown at 21^a and 22^a. The seal 24 of the form previously described is placed in position to engage both of these straps and one arm of the 30 seal is positioned over the overlapping ends of one strap so that when the seal is subsequently operated upon by a sealing tool to form the depressions 24^a in the edges of the strap and thereby partially shear the edges 35 of the seal and the straps, the seal is united with the straps and at the same time the overlapping ends of the straps are secured together.

40 Although one form of the improved seal has been shown and described, it will be understood that it may be constructed in various other forms within the scope of the appended claims.

I claim:

45 1. The combination with a pair of crossed straps angularly disposed, of a sealing device having angularly disposed arms each engaging one of said straps, said arms having flanges underlying said straps, said arms and 50 said straps having parts thereof deflected at their edges to form interlocking connections.

55 2. As an article of manufacture, a seal comprising a flat metal plate having angularly disposed arms, said arms having parallel flanges extending laterally in the same direction from their edges.

60 3. The combination with a pair of crossed straps overlapping each other, the ends of each strap being arranged to overlap adjacent the other strap, of a sealing device having angularly disposed parts engaging both of said straps and the overlapping ends thereof to secure said overlapping ends and prevent relative movement of said straps.

65 4. The combination with a pair of crossed

straps overlapping each other, the ends of each strap being arranged to overlap adjacent the other strap, of a sealing device having angularly disposed arms each adapted to engage the overlapping ends of one of said straps, said arms having flanges adapted to be bent around said straps, said seals and said straps having projections produced in the edges thereof to form an interlocking connection between the ends of each strap and the cooperating part of said seal.

70 5. The combination with a pair of crossed metal straps, of a sheet metal sealing device having angularly disposed arms each engaging one of said straps adjacent the crossing thereof, said arms having flanges bent over said straps, said arms and said straps having parts thereof offset transversely to provide an interlocking connection between each arm and one of said straps.

75 In testimony whereof, I have subscribed my name.

80 JOHN EKERN OTT.
